COLOR TELEVISION PROJECTOR

Christian C. Larson, Fort Wayne, Ind., assignor,
by mesne assignments, to Farnsworth Research
Corporation, a corporation of Indiana

Application April 15, 1946, Serial No. 662,378

5 Claims. (Cl. 178—5.4)

1

This invention relates to television systems and particularly to an optical device for use in producing a television image in color.

A color television system which is commonly used employs a single cathode ray tube for reproducing in succession a plurality of partial images. Each partial image represents one of a number of primary color components of the television subject. Each of these partial images is reproduced in black and white on the screen of the tube. A colored disc or drum is rotated between the fluorescent screen of the cathode ray tube and the observer, so that as each black and white representation of one of the primary color components of the subject is reproduced on the screen, a correspondingly colored filter element of the disc or drum is between the observer and the screen. The final result is a colored reproduction of the television subject.

All of such systems require, in the first place, a movable color filter device either in the form of a disc, a drum or the like. The filter apparatus must be rotated or otherwise moved in substantial synchronism with the successive reproductions of the partial television images. Such apparatus either is required to operate at a relatively high speed or the device must consist of a relatively large number of color filter elements in order to produce the desired effects.

Ordinarily, a television receiver is provided with a cathode ray tube which, when directly viewed, will produce only a relatively small picture. It is becoming increasingly desirable to project images from such tubes so that a relatively large picture may be produced on a viewing screen. One of the most satisfactory optical systems for use in a television projector is a modification of the Schmidt camera used to some extent heretofore in astronomical telescopes and the like.

In order to use a reflection type of optical system such as that based on the Schmidt camera in a television receiver for projecting colored images upon a viewing screen, it usually has been necessary to sacrifice a substantial portion of the light projecting properties of such an optical system. For example, in one proposed use of a Schmidt optical system in a color television projection receiver, a color filter drum having a great many color filters is rotated in close proximity to the fluorescent screen of the cathode ray tube. Inasmuch as this screen must also face the spherical reflecting member of the optical system, it has been necessary to thread the color filter drum through suitable slots in the spherical

reflector. Then when the desired color filter is passing before the screen of the cathode ray tube, the properly colored light representing the corresponding color component of the television subject is projected onto the spherical reflector. In that section of the reflector through which the filter drum operates the desired colored image is reflected back through other segments of the color drum. If the desired color is say red, the rays of light reflected from the central portion of the reflector will impinge upon green and/or blue filter segments. The reflected red rays which impinge upon these green and blue filter segments are absorbed to a great extent thereby and, therefore, do not materially impair the color reproduction. Alternatively, it has been proposed to mask these filter segments which are not in use at any given instant so that the colored light rays reflected from the mirror will not impinge upon these segments. In any case, a substantial portion of the spherical mirror is not used for the enlarged reproduction of the image. In other words, the otherwise efficiently operating Schmidt optical system is not employed at maximum efficiency.

It, therefore, is an object of this invention to provide an optical system of the reflection type which will function at high efficiency in a television projection system.

Another object of the invention is to provide optical apparatus for use in conjunction with a Schmidt optical system for projecting colored television images onto a viewing screen without materially reducing the efficiency of the Schmidt system.

In accordance with this invention, there is provided the usual concave reflecting mirror and preferably, in addition, an aspherical correcting plate if the concave mirror is spherical as in the Schmidt camera. A number of cathode ray reproducing tubes are directed generally toward the central axis of the system at a point between the concave mirror and the focal surface area thereof. In addition, there are provided a number of plane reflectors, one for each tube, which are located relative to the concave mirror and to the respective tubes in such a manner that they will reproduce in the focal surface area of the concave mirror a plurality of virtual images exactly in register corresponding to each of the cathode ray tube screens. In a color television system some or all of the images may be of different elementary colors.

For a better understanding of the invention, together with other and further objects thereof,

reference is made to the following description, taken in connection with the accompanying drawings, and its scope will be pointed out in the appended claims.

In the accompanying drawings:

Fig. 1 is a side elevational view showing diagrammatically one form of apparatus embodying the invention; and

Fig. 2 is a sectional view taken on the line 2—2 of Fig. 1.

Having reference now to the drawings, there is shown a concave reflector 11. Preferably, as in the Schmidt camera, this reflector is spherical. There also is provided a light refractive device 12 such as a lens having a particular configuration to correct for the spherical aberration of the reflector 11. The corrector plate 12 is located substantially coaxially with the spherical reflector and is spaced therefrom at such a distance that it lies substantially in the same plane as the center of curvature of the reflector. The spherical reflector has a predetermined focal surface area which also has a spherical configuration and is represented by the broken line 13.

The optical system in accordance with this invention also is provided with a plurality of plane reflectors which, in the illustrative embodiment, comprise three contiguous faces of a cubical member 14. The plane reflectors which are used comprise the faces 15, 16 and 17. All three of these plane reflectors meet at a common point which is located on the central axis 18 of the projecting optical system. The plane reflectors are located between the spherical reflector 11 and its focal surface area 13 and face generally the concave reflecting surface of the spherical reflector.

The system also includes a plurality of cathode ray television reproducing tubes. In the case where three plane reflectors are used, there are employed three tubes 19, 21 and 22. The tube 19, for example, is arranged so that the fluorescent screen which is formed on the face of the tube is directed toward the plane reflector 15. The tube 19 is located at such an angle with respect to the plane reflector 15 that the image of the fluorescent screen of the tube is reflected from the plane reflector 15 onto the spherical reflecting surface of the reflector 11 in such a manner that the light rays which impinge upon the reflector 11 appear to originate at the focal surface area 13. In other words, the tube 19 and the plane reflector 15 are so located relative to one another and to the spherical reflector 11 that a virtual image of the fluorescent screen of the tube 19 is formed in the focal surface area 13. In a similar manner, the tubes 21 and 22 are located respectively relative to the plane reflectors 16 and 17 to effect reflected reproductions of their fluorescent screens in the spherical reflector 11. The tubes 21 and 22 likewise are located so as to produce virtual images of their respective screens in the focal surface area 13.

Between the fluorescent screen of the tube 19 and the plane reflector 15, there is mounted a color filter 23. Similarly placed color filters 24 and 25 are provided in conjunction with the tubes 21 and 22 respectively. Depending upon the particular mode of operation of such a device, as will be explained in greater detail subsequently, the color filters 23, 24 and 25 each may be different from the others or each may have other forms to be described. In one form of the invention, the color filter 23 may be red, the filter 24 green, and the filter 25 blue, for example. In

such a case the filters will be mounted in a stationary manner in front of the associated tube screens.

Inasmuch as there are provided a plurality of cathode ray tubes in accordance with this invention, the fluorescent screens of these tubes each may be formed by different phosphors so that the images reproduced on the screens may be in the desired elementary colors. In such a case, the color filters may be eliminated.

Referring now to a preferred mode of operation of the described apparatus embodying the invention, assume that the color filters 23, 24 and 25 are respectively red, green and blue. In such a case, they are stationary. The television communication system employed to operate the cathode ray tubes 19, 21 and 22 may be entirely conventional. Such a system operates by transmitting in succession trains of video signals representing respectively red, green and blue partial images of a subject. In such a case, the video signals representing the red partial image are impressed upon the tube 19. These signals produce on the screen of the tube 19, a black and white representation of the red portion of the subject. The light emanating from the face of the tube passes through the red color filter 23 to produce a red colored partial image on the plane reflector 15. By reason of the described relationship between the tube 19, the plane reflector 15 and the spherical reflector 11, this red partial image is projected by the optical system comprising the spherical reflector 11 and the corrector plate 12 onto a viewing screen (not shown).

In like manner, the video signals representing the green portion of the subject are impressed upon the cathode ray tube 21 which, in conjunction with its associated green filter 24, produces a green partial image on the plane reflector 16. Similarly, the video signals representing the blue portion of the subject are impressed upon the tube 22 which in cooperation with its associated color filter 25 produces a blue partial image on the plane reflector 17.

Inasmuch as the cathode ray tubes and the plane reflectors are located relative to one another in the manner described to produce, respectively, virtual images of the fluorescent screens in the focal surface area 13, all of the partial images will be reproduced on the viewing screen exactly in register.

In order to operate the tubes 19, 21 and 22 substantially in the manner described, a switch 55 which preferably should be electronic may be used to transfer the video signal circuit from one tube to another as the corresponding color signals are received. Alternatively, three separate signaling channels may be provided, one for each of the color components of the picture so that all of the video signals may be transmitted and received for each of the colors substantially simultaneously.

If the plane reflectors 15, 16 and 17 form three contiguous faces of a cube as illustrated and described, the cathode ray tubes 19, 21 and 22 will be arranged substantially as shown. In such a case, the image of the screen of the tube 19 which is reflected by the plane reflector 15 will use less than the entire surface of the spherical reflector 11. Similarly the tubes 21 and 22 each will not utilize the entire surface of the spherical reflector. However, other angular positions of the plane reflectors may be used as subsequently described, whereby greater portions of

the spherical reflector surface may be used by each of the tubes.

It may be desired to increase the brilliancy of the reproduced picture. In this event, the received video signals may be applied simultaneously to all of the tubes. This will necessitate the use of color filters associated with each of the tubes which will include all three colors. They will require rotation or other movement in the usual manner to coincide with the image which is being reproduced by the tube. Synchronism between the moving color discs, drums or the like may be effected in the usual manner. Nevertheless, by means of the present invention the color filters may be located entirely out of the path of any reflected light rays.

It obviously is not necessary to employ plane reflectors which form three faces of a cube. If such a structure is used, the plane reflectors, of necessity, are mutually disposed at right angles. Other angular relationships between the plane reflectors may be employed within the scope of this invention. For example, each of the reflectors may be placed more nearly in a plane perpendicular to the central axis 18. The cathode ray tubes associated with such reflectors will be located closely to the spherical reflector 11. In some cases, it may be desirable to so position the plane reflectors that the cathode ray tubes will be located behind the spherical reflector. In such a case, suitable apertures may be provided in the spherical reflector to enable light to be projected from the tube screen onto the associated plane reflector. In cases where the plane reflectors are set in planes more nearly perpendicular to the central axis of the system, the light which is reflected therefrom will fall upon a greater surface area of the spherical reflector 11. More efficient operation may be obtained in some cases by so locating the plane reflectors and their associated tubes. Substantially any desired location may be employed so long as the relationship between each of the plane reflectors and its associated cathode ray tube is such that there is produced a virtual image of each tube screen in the focal surface area 13.

Obviously, the apparatus embodying the present invention is not limited to the use of three plane reflectors. Other numbers of plane reflectors either greater or smaller may be used with equal facility in order to obtain special effects without departing from the spirit of the invention.

While there has been described what, at present, is considered the preferred embodiment of the invention, it will be obvious to those skilled in the art that various changes and modifications may be made therein without departing from the invention, and it is aimed, therefore, in the appended claims to cover all such changes and modifications as fall within the true spirit and scope of the invention.

What is claimed is:

1. An image projecting device for a color television system comprising, a concave spherical reflector having a predetermined focal surface area, a plurality of plane reflectors angularly disposed relative to one another and facing said spherical reflector, a plurality of cathode ray television reproducing tubes having the fluorescent screens thereof directed toward respective ones of said plane reflectors, said tubes and said plane reflectors being so located relative to one another and to said concave reflector as to produce virtual images of said fluorescent screens

substantially in register in the focal surface area of said concave reflector, and means for directing differently colored light from each of said plurality of tubes onto its corresponding plane reflector.

2. An image projecting device for a color television system comprising, a concave reflector having a predetermined focal surface area, an auxiliary reflecting device facing said spherical reflector, said auxiliary reflecting device comprising a plurality of plane reflectors, a plurality of cathode ray television reproducing tubes having the fluorescent screens thereof directed toward respective ones of said plane reflectors, said tubes and said plane reflectors being so located relative to one another and to said concave reflector as to produce a plurality of virtual images of said fluorescent screens substantially in register in the focal surface area of said concave reflector, and means associated with each of three of said tubes in conjunction with the corresponding plane reflector to produce three partial images of said television subject in three different colors.

3. An image projecting device for a color television system comprising, a concave spherical reflector having a predetermined focal surface area, a light refractive device facing said reflector for correcting the spherical aberration of said reflector, an auxiliary reflecting device located between said spherical reflector and its focal surface area, said auxiliary reflecting device comprising a plurality of plane reflectors symmetrically disposed around the central axis through said spherical reflector and said refractive device, a plurality of cathode ray television reproducing tubes having the fluorescent screens thereof directed toward respective ones of said plane reflectors, said tubes and said plane reflectors being so located relative to one another and to said spherical reflector to produce of plurality of partial virtual images of a television subject in the focal surface area of said spherical reflector, and colored light filters located between each of said tubes and its corresponding plane reflector.

4. An image projecting device for a color television system comprising, a concave spherical reflector having a predetermined focal surface area, a lens facing said reflector and spaced therefrom for correcting the spherical aberration of said reflector, an auxiliary reflecting device located between said spherical reflector and its focal surface area, said auxiliary reflecting device comprising three plane reflectors angularly disposed relative to one another in a symmetrical manner about the central axis through said spherical reflector and said lens, three cathode ray television reproducing tubes having the fluorescent screens thereof directed toward respective ones of said plane reflectors, said tubes and said plane reflectors being so located relative to one another and to said spherical reflector as to produce three respective virtual images of said fluorescent screens in substantial register in the focal surface area of said spherical reflector, and a differently colored light filter located between each of said tubes and its associated plane reflector.

5. An image projecting device for a color television system comprising, a concave spherical reflector having a predetermined focal surface area, a spherical aberration corrector plate facing said reflector and spaced therefrom, an auxiliary reflecting device located between said spherical reflector and its focal surface area, said auxiliary reflecting device comprising three plane reflectors

mutually disposed at right angles, the common point of said three plane reflectors being located on the central axis through said spherical reflector and said corrector plate and being pointed toward said spherical reflector with the plane reflectors disposed symmetrically about said axis, three cathode ray television reproducing tubes having the fluorescent screens thereof directed toward respective ones of said plane reflectors, said tubes and said auxiliary plane reflectors being 10 located suitably relative to one another and to said spherical reflector to produce registering virtual images of said fluorescent screens in the focal surface area of said spherical reflector, and a differently colored light filter element located 15 between each of said tubes and the corresponding plane reflector.
